US00D872794S

(12) **United States Design Patent** (10) **Patent No.:** **US D872,794 S**
(45) **Date of Patent:** **** Jan. 14, 2020**

(54) **GLASSES WITH OPTICAL IMAGE SENSOR**

(71) Applicant: **BAE SYSTEMS plc**, London (GB)

(72) Inventor: **Mark Wilkins**, Rochester (GB)

(73) Assignee: **BAE SYSTEMS plc**, London (GB)

(**) Term: **15 Years**

(21) Appl. No.: **29/639,731**

(22) Filed: **Mar. 8, 2018**

(30) **Foreign Application Priority Data**

Sep. 8, 2017 (EM) 004247732-001

(51) **LOC (12) Cl.** **16-06**

(52) **U.S. Cl.**

USPC **D16/326**

(58) **Field of Classification Search**

USPC D16/300, 313, 314, 326, 309

CPC G02C 3/003

See application file for complete search history.

(57) **CLAIM**

The ornamental design for glasses with optical image sensor, as shown and described.

DESCRIPTION

FIG. 1 is a front view of glasses with optical image sensor according to the new design;

FIG. 2 is a top view thereof;

FIG. 3 is a perspective view thereof;

FIG. 4 is another perspective thereof; and,

FIG. 5 is a side view thereof.

The broken line showing of a head is included for the purpose of illustrating portions of the glasses with optical image sensor and form no part of the claimed design.

1 Claim, 4 Drawing Sheets
